ATTORNEY

UNITED STATES PATENT OFFICE.

LAWRENCE T. YENERALL, OF JEFFERSON, PENNSYLVANIA.

MINER'S-BATTERY HOLDER.

Application filed March 30, 1928. Serial No. 266,032.

My invention relates to devices for securing a miner's electric battery to the belt of the miner and it primarily has for its object to provide such a means as will be simple in construction, a device that can be made cheaply and applied to any belt and a device by the use of which the lamp can be quickly attached to the belt and as quickly removed when desired.

10 Further the invention seeks to provide a device of the character described which can be stamped from sheet metal.

With other objects in view which will be in part obvious and in part referred to hereinafter, the invention resides in those novel features of construction, combination and arrangement of parts hereinafter described and then specifically pointed out in the appended claims reference being had to the accompanying drawing, in which:

Figure 1 is a perspective view illustrating the invention, a battery being indicated in dotted lines.

Figure 2 is an elevation and part longitudinal section of the invention, and

Figure 3 is a detail cross section on the line 3—3 on Figure 2.

In the drawing in which like numbers of reference designate like parts in all the figures, 1 represents the belt to which the battery 2 is to be attached.

The invention comprises a base plate 3 which is riveted at 4 to the belt 1. To this base plate is secured, at 7, a hook member consisting of the base part 5 and the offset part 6, the latter lying in a plane parallel to that of the base plate 3 but spaced therefrom. To the base plate 3 is also fastened a housing 8 stamped from thin metal with tangs 9 to pass through slots 10 in the base plate 3 and be clinched over.

The housing 8 has a slot 11 in one end and an opening in the other end to permit passage of the latch member. This member consists of the head portion 12, the shank 13 and 45 the handle 14, the latter being wider than the slot 11 to serve as a stop. Springs 16 within the housing press the head 12 toward the hook 6, a washer 15 being used if desired to give a wider spring abutment. 50

In using my invention the loop 17 of the battery 2 is slipped over the hook 6, the head 12 having first been pulled back, after which the head 12 is permitted to slip within the loop 17 thereby securely holding the lamp to 55 the belt.

From the foregoing description, taken in connection with the accompanying drawing, it is thought the construction and uses of my invention will be readily understood by 60 those skilled in the art.

What I claim is:

1. As a new article, an attachment for miner's belts comprising a base plate, means securing said plate to a belt, a hook fixed to 65 said plate and having an offset portion lying approximately parallel to said plate, a housing secured to said plate, a spring pressed latch member mounted in said housing and having a head aligning with said offset portion for the purposes described. 70

2. The article of claim 1, wherein the housing is formed of sheet metal and has slots in its ends for the reception of said latch member, said latch member projecting 75 through said slots and having a handle constituting a stop, and a head connected with the handle by a shank, and springs in the housing for pressing the head forwardly.

LAWRENCE T. YENERALL.
